CLAIM

The ornamental design for a lid handle, as shown and described.

DESCRIPTION

4.1-6.4 Lid handle

4.1 : Perspective

4.2 : Front

4.3 : Top

4.4 : Cross-sectional view of 4.3

5.1 : Perspective

5.2 : Front

5.3 : Top

5.4 : Cross-sectional view of 5.3

6.1 : Perspective

6.2 : Front

6.3 : Top

6.4 : Cross-sectional view of 6.3

The arrows in the drawings do not form part of the design, they merely indicate the cross-sectional plane; the broken lines in the drawings depict portions of the lid handle that form no part of the claimed design.

The arrows in the drawings do not form part of the design, they merely indicate the cross-sectional plane; protection is not sought for the parts of the design represented with dashed lines.

1 Claim, 12 Drawing Sheets(56)
